CLAIM

We claim the ornamental design for a leg rigging clip, as shown and described.

DESCRIPTION

FIG. 1 is a perspective view of a leg rigging clip in accordance with a first embodiment of our new design; FIG. 2 is a front elevational view thereof, the rear elevational view being a mirror image thereof; FIG. 3 is a bottom plan view thereof; FIG. 4 is a top plan view thereof; FIG. 5 is a right side elevational view thereof; FIG. 6 is a left side elevational view thereof; FIG. 7 is a perspective view of a leg rigging clip in accordance with a second embodiment of our new design; FIG. 8 is a front elevational view thereof, the rear elevational view being a mirror image thereof; FIG. 9 is a bottom plan view thereof; FIG. 10 is a top plan view thereof; FIG. 11 is a left side elevational view thereof; and, FIG. 12 is a right side elevational view thereof. The broken lines depict unclaimed environmental subject matter and form no part of the claim.
